[57] CLAIM

The ornamental design for a combined terrarium and potting tray, as shown and described.

DESCRIPTION

FIG. 1 is a top plan view of a combined terrarium and potting tray showing my new design;

FIG. 2 is an enlarged fragmentary top plan view of the grid shown separately for clarity of illustration;

FIG. 3 is a front elevation view thereof, the rear being identical;

FIG. 4 is an exploded front elevational view thereof;

FIG. 5 is a left side elevational view thereof;

FIG. 6 is a right side elevational view thereof; and

FIG. 7 is a bottom plan view thereof.

FIG. 1

FIG. 2
